UNITED STATES PATENT OFFICE

BRANKO LAZICH, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRACK CIRCUITS

Application filed June 4, 1930. Serial No. 459,131.

My invention relates to railway track circuits, and has for an object the provision of means for reducing the time required for the release of a track relay armature when a train enters the associated section.

I will describe two forms of track circuit apparatus embodying my invention, and will then point out the novel features thereof in claims.

10 In the accompanying drawings, Fig. 1 is a diagrammatic view showing one form of track circuit apparatus embodying my invention. Fig. 2 is a view showing a modification of the apparatus shown in Fig. 1 and also 15 embodying my invention.

Similar reference characters refer to similar parts in each of the views.

Referring first to Fig. 1, the reference characters 1 and 1^a designate the track rails 20 of a railway, which rails are divided by insulated joints 2 to provide a track section A—B.

The reference character R designates a track relay having an armature 5 pivotally 25 mounted at 5^a, and biased by gravity to its open position wherein a front contact 6—6^a is open. The relay includes a main winding 3 for closing the armature 5 against the action of gravity, and an auxiliary winding 4 for 30 creating in the armature a flux which opposes the flux created by the main winding 3. The main winding 3 is connected across the rails of section A—B, a resistance 7 preferably being included in series with this winding. 35 The auxiliary winding 4 is connected across the rails of section A—B in series with the usual source of track circuit current, which, as here shown, is a battery C.

The windings 3 and 4 are so proportioned 40 that when the track section is unoccupied, the flux created by winding 3 is considerably greater than the flux created by winding 4, and that the resultant flux is sufficient to close the armature 5. When a train enters section A—B, however, the wheels and axles 45 will form a low resistance shunt across the main winding 3 and the resistance 7, so that the main winding 3 will be substantially de-energized, and the current flowing in the auxiliary winding 4 will be materially in-

creased. The flux due to the main winding 3, which is indicated by the solid arrow, will then be substantially zero, and the flux due to the auxiliary winding 4, which is indicated by the dotted arrow, will have a considerable value. It follows that the direction of the resultant flux due to the two windings will be reversed, so that the flux in the armature will pass through zero. This reversal of the direction of the flux through the armature will cause the armature to release more quickly than if the auxiliary winding 4 were not provided.

The parts of the relay must be so proportioned that when the track section A—B is 60 occupied by a car or train, the maximum resultant flux is not sufficient to close the armature 5.

Referring now to Fig. 2, the apparatus shown in this view is the same as that of Fig. 1, except that means are provided for cutting the auxiliary winding 4 out of the track circuit when the relay is open, so that this winding will not oppose the main winding 3 when the relay becomes energized. When the relay is energized, winding 4 is in the track circuit, the path being from rail 1^a through battery C, contact 7—6, and winding 4 to rail 1. When the relay is open, contact 7—6 is opened and contact 7—8 is closed, so that battery C is connected directly across the rails and winding 4 is excluded from the track circuit.

The safety factor required for railway track circuits is not affected by track circuits embodying my invention, because the breakage of any wire or the failure of the source of current C cannot cause the armature 5 to be falsely closed.

Although I have herein shown and described only two forms of track circuits embodying my invention, it is understood that various changes and modifications may be made therein within the scope of the appended claims without departing from the spirit and scope of my invention.

Having thus described my invention, what I claim is:

1. In combination, a section of railway track, a relay having a single magnetic cir-

cuit including an armature biased by gravity to the open position, said magnetic circuit being provided with a main winding for closing said armature as well as an auxiliary winding for creating in said magnetic circuit and in said armature a flux which opposes and is weaker than the flux created therein by said main winding, a connection across the rails of said section including said main winding, and a second connection across the rails of said section including said auxiliary winding and a source of current in series.

2. In combination, a section of railway track, a relay having two cooperating windings, a connection across the rails of said section including one of said windings, a second connection across the rails including the other of said windings and a source of current in series, and means for excluding said second winding from said second connection when the relay is open.

3. In combination, a section of railway track, a relay having an armature biased by gravity to the open position and a main winding for closing said armature as well as an auxiliary winding for creating in said armature a flux which opposes and is weaker than the flux created therein by said main winding, a connection across the rails of said section including said main winding, a second connection across the rails including said auxiliary winding and a source of current in series, and means for excluding said auxiliary winding from said second connection when the relay is open.

In testimony whereof I affix my signature.
BRANKO LAZICH.
